UNITED STATES PATENT OFFICE.

THOMAS J. FEGLY AND GEORGE O. LEOPOLD, OF PHILADELPHIA, PENNSYLVANIA, ASSIGNORS TO NORTH BRO'S M'F'G. CO., OF PHILADELPHIA, PENNSYLVANIA, A CORPORATION OF PENNSYLVANIA.

DISPLAY TOOL HOLDER.

Application filed December 17, 1925. Serial No. 75,993.

The object of our invention is to construct a device for holding tools, such as push screw-drivers and drills, in operative position on a display base or stand, in order that an intending purchaser may try the tool, the tool being so connected to the holding device that it cannot be removed readily. 5

In the accompanying drawing:

Fig. 1 is a perspective view of our improved tool-holding device, showing the tool in position;

Fig. 2 is a vertical sectional view;

Fig. 3 is a detached perspective view illustrating details of the invention;

15 Fig. 4 is a sectional view of the device arranged to display drills and their bits;

Fig. 5 is a view illustrating a modification of the invention;

20 Fig. 6 is a perspective view of another modification; and

Fig. 7 is a vertical sectional view of the device shown in Fig. 6.

On a base 1 of any suitable form is mounted a tool-holding device 2. This device has 25 a threaded opening at its lower end to receive the threaded portion of the retaining screw 3, which extends through an opening in the base 1. The screw in the present instance has an annular groove 4, in which 30 is a washer 5 resting in a recess in the underside of the base. In the upper end of the retaining screw 3 is a socket 6, in which is located a freely rotatable plug 7, having a transverse slot in its upper end to receive 35 the bit of a screw-driver.

At the upper end of the tool-holding device is a bearing 8 for the shank 9 of a screw-driver bit 10, in the present instance. On the shank directly under the bearing is 40 a collar 11 secured to or forming part of the bit. The blade of the bit extends into the slot in the plug 7, and the collar is so located as to retain the blade in engagement with the plug at all times. A portion of 45 the tool which actuates the bit is shown at 12, and in the present instance is a push screw-driver.

To operate the push screw-driver, it is pushed to turn the bit which also turns the 50 plug. A spring in the screw-driver returns

the handle end of the driver to its normal position as soon as it is released. The bit can be turned to the right or left by moving the shifter 13. This type of screw-driver is one of many different types now 55 on the market.

If a push-drill is to be displayed, then the bit 10^a is in the form of a drill bit, as shown in Fig. 4. The end of the bit rests in a conical recess 6^a in the lower end of the display device, the upper end of the bit extending through a bearing 8^a. The bit is provided with a collar 11^a, as in Fig. 2. The device 2^a has an extension 3^a located in an opening in the base and is held in place by 60 a screw and washer.

Fig. 5 illustrates a modification, in which the display device is arranged to be secured to a base or other support by ordinary wood screws, and in the bottom of the device is a 70 cylindrical support 3^b for a plug 7^b, having an enlarged head which is slotted to receive the blade of the screw-driver. In this case, the bit 10^b is held in place by the enlarged portion of the bit, the bit being passed 75 through the opening for the cylindrical supports 3^b before the support is in position, and prior to the attachment of the device to the base.

In Figs. 6 and 7 are shown modifications, 80 in which the bearing 8^c has a circular opening for the bit, and slots at the opposite side of the opening to allow the wide portion of the bit to pass through the opening. When the bit is in place, it is difficult to remove 85 it, as the wide portion of the bit must be brought in exact alignment with the slots.

The plug 7^c in this instance has a flange at its lower end, and the opening for the plug has an internal flange. Between the 90 two flanges is a spring 14, which places sufficient friction on the plug to allow a ratchet tool to operate.

The above described device can be mounted on a display stand either singly as shown 95 in Fig. 1 or may be grouped with other devices for displaying tools as desired.

Purchasers of tools, especially those of comparatively new design, desire to operate 100 the tools before purchasing. By mounting

the tools on display stands such as described above, the tools can be operated in the same manner as when in use, and they cannot be readily removed from the holders by malicious persons.

We claim:

The combination in a holding device for displaying tools, of a base; a tool-holder on the base, said holder having a threaded opening in its lower end and having a bearing at its upper end; a screw extending

through the base and into the threaded opening of the tool-holder, said screw having a socket in its upper end; a plug located in the socket; the bearing and the plug arranged to receive a bit which extends through the bearing and engages the plug; and means for retaining the bit in engagement with the plug.
